Primary Examiner—Marcus A. Jackson

(57) **CLAIM**

The ornamental design for a monument sign, as shown and described.

DESCRIPTION

FIG. 1 is a front view of the monument sign of our design, it being understood that the opposite side not shown is a substantial mirror image thereof.

FIG. 2 is a top view of the monument sign.

FIG. 3 is a left side view of the monument sign, it being understood that the opposite side not shown is a substantial mirror image thereof; and,

FIG. 4 is a bottom view of the monument sign.
